UNITED STATES PATENT OFFICE.

ROBERT GRAY, OF GLASGOW, SCOTLAND, ASSIGNOR TO LANSTON MONOTYPE MACHINE COMPANY, OF PHILADELPHIA, PENNSYLVANIA, A CORPORATION OF VIRGINIA.

PRINTER'S STRIP-MATERIAL MOLD.

1,414,464.

Specification of Letters Patent.

Patented May 2, 1922.

Application filed July 19, 1919. Serial No. 311,933.

To all whom it may concern:

Be it known that I, ROBERT GRAY, a subject of the King of Great Britain, residing at 131 Kirkintilloch Road, Bishopbriggs, 5 Glasgow, Scotland, have invented certain new and useful Improvements in Printers' Strip-Material Molds; and I do hereby declare the following to be a full, clear, and exact description of the same, reference being had to the accompanying drawings, 10 forming part of this specification, and to the characters of reference marked thereon.

This invention relates to molds for the production of printers' strip material, such as rules, borders and similar elements of 15 printers' forms having ornamental, non-continuous, interrupted or otherwise varied printing surfaces and has for its principal object to provide improved or simplified 20 and efficient mechanism for producing this material in type or like metal.

An embodiment of the invention is shown in the accompanying drawings in which—

Fig. 1 is a plan view
25 Fig. 2 is a longitudinal section, and
Fig. 3 is a detail of the design producing mechanism.

The mold shown in the drawings is of the general type illustrated in United States Patent No. 1,222,415 dated April 10, 30 1917. Such mold is commercially well known for producing fused increment strip material for printing forms; in the form shown in which a rule matrix is employed, 35 the material produced is type high and has a printing face consisting of a single line or a plurality of parallel lines according to the formative cavity of the particular matrix used.

40 The present invention contemplates a mold of the type referred to or of any other suitable type for producing printers' rules, embodying as a part of the mold structure a design producing device for 45 altering or varying the single or parallel line rule produced by the matrix, whereby a non-continuous, interrupted or otherwise varied design may be produced. The line rule is thus transformed into what may be 50 called a fancy rule or border.

The casting elements of the mold in which the invention in its preferred form is incorporated and in connection with which it will be described, are preferably con-

structed in accordance with the invention 55 set forth in the above mentioned patent. It is deemed unnecessary for the purposes of the present application to give a detailed description of said elements but certain important parts will be referred to for 60 identification purposes and for making clear the disclosure of the invention. Reference characters corresponding with those of the patent will be used to refer to identical parts. 65

The casting elements comprise a base 3 with two upwardly extending portions 4 connected across the top by two tie bars 5, secured to the walls 4 by screws; and also side or type blocks 8 and 9 between which 70 a mold dimensioning and ejecting blade 27 reciprocates. The bottom, sides and one end wall of the mold cavity are formed by the base block 3, the side blocks 8 and 9 and the mold blade 27 respectively. The side of 75 said cavity opposite the mold blade is open for the ejection of the cast and this opening is closed during casting by the rear end of the previous cast of strip material. The top of the cavity is closed by the matrix 21 80 held in position by suitable clamping mechanism. The cast strip 65 is ejected or fed forward by the advance of the mold blade 27 which is then retracted and a fresh charge of molten metal injected into the cavity. 85 In the preferred method of operation the incoming metal fuses that portion of the rear end of the previous cast which has been left to form the forward wall of the cavity, then congeals in union with said previous cast and 90 in turn is fed forward by the next advance of the mold blade. Thus the repeated casting and feeding produces a fused increment strip which is intermittently fed from the mold. After being cast and cooled each increment fed forwardly by the mold blade, 95 enters an exit channel formed by an extension of the side blocks. The forward feeding of subsequent casts accomplishes the removal from the channel and to the exterior of the 100 mold of preceding increments. A friction device or clamp operated by a screw 18 is provided for imposing a certain degree of resistance to the forward movement of the strip and for retaining the strip during casting in 105 the position to which it has been fed. The screw 18 is conveniently operated by connecting it with a movable part of the machine

with which the mold is adapted to be used. The mold blade 27 is also connected with a part of such machine and the injection of molten metal through the nozzle 20^a is accomplished by the pump or other equivalent mechanism of such machine, it being understood that these operations of clamping, injecting, and reciprocating the mold blade are carried on in properly timed relation.

- 10 The matrix 21 preferably has a formative cavity 22 and gives shape or pattern to the upper or printing face of the strip. The formative cavity 22 consisting, as shown, of a groove or of parallel grooves is closed at 15 one end and open at the exit end so that the strip material can be fed forward to remove it from the cavity without injuring the cast printing surface. On account of this ejecting or removing operation, it will be 20 readily understood that the strip material will have a printing face in the form of a continuous, single line or of a plurality of continuous, parallel lines.

According to the present invention a non- 25 continuous or interrupted design is given to the strip by means of the design producing device in the form, as shown, of a roller 41 having the design formed on its periphery and mounted over the channel through which 30 the strip material passes before its complete ejection from the mold. A suitable place for mounting this roller is, as shown, in the forward tie bar 5 so that the device operates upon the strip immediately subsequent to 35 its removal from the casting cavity. The bar 5 is provided with a bore for receiving the spindle 42 upon which the roller 41 is adapted to rotate in a cleft 43 open at the bottom and of such width, shown particularly 40 in Fig. 3 as to guide the roller and prevent it from moving laterally with respect to the strip. The spindle 42 extends beyond the end of the tie bar 5 and may be provided with a knurled head 44. The spindle may 45 have a grooved portion 42^a (Fig. 1) in proximity to the tie bar securing screw 45 so that when the spindle and roller have been assembled in the tie bar and the latter assembled in the mold, the securing screw 45 when 50 inserted will enter the spindle groove 42^a and may be tightened without interfering with the spindle. The latter, on the other hand, will be prevented from withdrawing by contact of the walls of the groove 42^a 55 with the screw 45 and all parts will be thus securely locked in place.

The roller 41 in the present embodiment is designed and arranged to produce a strip having a printing surface consisting of a 60 wide line bearing a series or succession of non-printing dots so that the printed product would be white dots on a black band. It will be understood of course that the design shown is illustrative merely, it being evident 65 that practically any desired design may be

used. The periphery of the roller 41, as shown, is provided with spaced conical projections 41^a which penetrate into the broad line continuous printing face formed by the matrix 21, the formative cavity 22 of which 70 in the instance taken consists of a single cavity having a width substantially equal to the point size or thickness of the strip produced by the mold. The penetration of the projections 41^a alters such printing face 75 by producing an interrupted or non-continuous pattern in the form of spaced circular depressions which do not receive ink and therefore do not print.

The operation of casting the strip proceeds in the well known manner and there is produced by the mold and the matrix 21 a broad line rule the printing face of which 80 engages with the peripheral surface of the roller 41 causing the latter to rotate and alter the said face in accordance with the design with which the peripheral surface of the roller is provided. The function of alteration is brought about automatically by the movement of the strip itself and the production of a fancy design is thus accomplished 85 without the necessity of employing special and complicated mechanism. When it is desired to remove the design producing mechanism the forward tie bar 5 is removed from 90 the mold, the spindle 42 is withdrawn by the knurled head 44 and the roller 41 is allowed to drop out of the cleft 43. In assembling the roller is placed in the cleft, the spindle inserted in the tie bar and through 95 the roller and the tie bar is then placed in position. When the screw 45 is inserted a portion of it will enter the groove 42^a and thus lock the spindle in place.

I claim:

1. A mold for producing printers' fancy strip material embodying walls forming a cavity for receiving molten metal, means for removing the cast metal from the cavity and design producing mechanism operative on a 110 face of the cast metal subsequent to its removal from the said cavity.

2. A mold for producing printers' fancy strip material embodying base and type blocks to form a cavity for receiving molten 115 metal and an exit channel forward of said cavity, means for feeding the cast metal from the cavity into said channel and design producing mechanism mounted adjacent to said channel to alter a face of the 120 cast metal while in said channel.

3. A mold for producing printers' fancy strip material embodying base and type blocks to form a cavity for receiving molten 125 metal and an exit channel forward of said cavity, means for feeding the cast strip from the cavity into and through said channel, a wheel having a design formed on its periphery in position to engage with a face of said strip during its feeding movement to 130

alter said face in accordance with said design.

4. A mold for producing printers' fancy strip material embodying walls forming a cavity for receiving molten metal, means for feeding the cast metal forwardly from said cavity and design producing mechanism mounted forwardly of said cavity to engage with the strip and be operated automatically thereby during the feeding movement of said strip to produce a design upon a face thereof.
5. A mold for producing printers' fancy strip material embodying base and type blocks to form walls of a cavity for receiving molten metal and an exit channel forward of said cavity, a mold blade and a matrix also forming walls of said cavity, said blade being movable to feed the cast strip from said cavity into and through said channel, a wheel having a design upon the periphery thereof, and being rotatably mounted above the said channel with said periphery in position to engage with the matrix formed face of said strip during its feeding movement through the channel to alter said face in accordance with said design.
- 20 25

6. A mold for producing printers' fancy strip material embodying walls forming a

cavity for receiving molten metal, means for removing the cast strip from the cavity, a stationary matrix forming one wall of the cavity, said matrix being constructed to produce on one face of the strip a line printing surface, and design producing mechanism operative on said printing surface subsequent to the removal of the strip from the cavity to alter the cast printing surface thereof.

7. The combination with a monotype mold, of a roller having a design on the periphery thereof and arranged to engage with and roll upon a bar of type metal as it issues from the monotype mold.

8. The combination with a monotype mold, of a roller having a design upon the periphery thereof and arranged to roll upon a bar of type metal cast in said mold.

9. In the art of casting a bar of type metal, the method of casting a bar having a design upon one edge thereof and subsequently passing the bar in contact with the roller having a design on the periphery thereof for changing the design on the edge of the bar of type metal.

ROBERT GRAY.
